(57) **CLAIM**

The ornamental design for a lens cover for light fixture for indoor grow application as shown and described.

DESCRIPTION

FIG. 1 is a perspective view depicting a lens cover for light fixture for indoor grow application;

FIG. 2 is a bottom perspective view depicting the lens cover of FIG. 1;

FIG. 3 is a cross sectional view taken along the line 3-3 in FIG. 1;

FIG. 4 is a cross sectional view taken along the line 4-4 in FIG. 1;

FIG. 5 is a bottom elevation view depicting the lens cover of FIG. 1;

FIG. 6 is a top elevation view depicting the lens cover of FIG. 1;

FIG. 7 is a front side view depicting the lens cover of FIG. 1, the rear side view being a mirror image thereof; and, FIG. 8 is a right side view depicting the lens cover of FIG. 1, the left side view being a mirror image thereof.

The details shown in broken lines in the figures form no part of the claimed design for the lens cover for light fixture for indoor grow application. The dot-dash broken lines represent the bounds of the claimed design.

1 Claim, 5 Drawing Sheets
